UNITED STATES PATENT OFFICE.

ANTONIO CALVET RIFÉ, OF BARCELONA, SPAIN.

SHEDDING MECHANISM.

Application filed June 19, 1926, Serial No. 117,200, and in Spain August 31, 1925.

Many are the advantages which the new apparatus offers in relation to those known under the name of "dobbies"; in the first place, its absolute security and regularity in operation while in the case of the former, the ribs of wood, the plugs screwed on to them, the mechanism of a plurality of complicated small parts with needles and hooks, are mechanisms complicated and fragile in the extreme, and give rise to frequent breakages and constant errors and in consequence a production of defective pieces.

In this new apparatus the simplification of the mechanism has been reduced to its utmost limit, thereby giving to the various elements embodying my invention, a rigidity capable of resisting a maximum stress thus preventing all breakage and faults generally experienced in previous devices.

Furthermore, over the mechanism known as the "Segment system" it has likewise numerous advantages, seeing that the new apparatus is placed above the loom and moved by a simple rod, which enables immediately any irregularity in operation to be detected, the opposite of what occurs in the case of those in which the delicate mechanism of contact, which is effected by means of small pulleys placed within a small stop with a single point of support, is totally obstructed by large discs and where with frequent breakages of the small pulleys, stops and levers, the segment continues to operate, causing the consequent defects.

Other important advantages of the invention will be in part obvious and in part pointed out hereinafter.

In order that the invention and its mode of operation, may be readily understood by those skilled in the art, I have in the accompanying drawings, set out one possible embodiment of the invention.

In these drawings—

Figure 1 is a side elevation of the device, Figure 2 is a similar view showing the opposite side of the device,

Figure 3 is an end view of the same, and

Figure 4 is a vertical longitudinal sectional view showing cooperative action of the levers and the cams.

The machine consists of a frame, constituted by two benches 1 and 2 fastened together by means of the cross-pieces 3, 4 and 5. The frame thus formed is arranged over the loom and fixed to the jamb-posts of the

said loom by the feet 1' and 2' of the benches 1 and 2 respectively.

In the framework itself is fixed an axle 6 on which are freely mounted the levers 7, each of which support by one of its extremities 7', the rod of suspension of the respective heald, while at the other extremity they form the support 8, of a pulley or roller 9, against which acts the respective cam 10, which is rigid with the axle 11, mounted likewise on the framework 1, 2. The number of cams 10, mounted on the aforementioned axle, is equal to that of the levers 7, and their profile is variable in accordance with the movements which they are to transmit. The said levers are guided laterally by means of the cross pieces 4 and 5, for which purpose the latter are formed with the openings 4' and 5' respectively, for the passage of the levers. Furthermore on the plate 4, corresponding to the arm 7' of the lever 7, is arranged a horizontal plate 12, on which rest the levers 7, and whose position can be adjusted at will.

The axle 11, has fixed upon it, at one of its extremities a ratchet wheel 13, operated by a system of two pawls 14, which by the action of the spring 15 tend constantly to work against the same. The pawls referred to, have a common axis of rotation 16 and this is mounted on a lever 17, rigid with an axle 18, which at one end has joined to it the tension rod 19, which transmits the movement of the loom to the afore-mentioned lever. The latter, furthermore, is provided on its opposite arm with a balance-weight 20. The arrangement of the double system of pawls serves the purpose of attaining the working of the machine at every movement, both upwards and downwards of the tension rod 19.

Furthermore on the axle 11 itself, is mounted the brake 21, designed to counterbalance the abrupt action of the springs which work on the shafts, and at its opposite end it carries likewise fixed a toothed pinion 22, which transmits its movement to a wheel 22' to which is rigidly attached the star wheel 23, which, together with the sector 24, having the stops 25, which can impose themselves between its teeth, constitute the mechanism of retention and escape-ment of this machine, designed to ensure good working. The sector has its axis at 26, and is set in action by means of the

tension rod 27, joined to the same and to the lever 28, rigid with the axle 18, so that the sector follows the movements of the lever 17.

With the apparatus described can be obtained various sorts of texture of warp with the woof, this variety of texture being obtained by the application of cams of different throws and the number of shafts and levers, can be equally variable according to 10 the fabric required. Moreover, each shaft of the loom rises with a single lever as described, but it can be also actuated by means of a double lever.

It is to be understood that the invention 15 is capable of many modifications and those modifications that are within the scope of the claims, I consider within the spirit of the invention.

As a basis of this patent there is claimed 20 as follows:

1. A shedding mechanism comprising in combination with levers, operating cams, a movable arm, a pawl member carried by said arm, means rigidly mounted with said cams 25 and engaged by the pawl member for rotating the cams, and means associated with said arm and cams for locking and freeing the latter with movement of the arm.

2. A shedding mechanism comprising in 30 combination with levers, operating cams, a movable arm, a double pawl carried by said arm and adapted to move therewith, a ratchet rigidly mounted with said cam and engaged by the pawls for rotating the cams, 35 gearing rigid with the cams, and means

moving in unison with said arm and engageable with said gearings for locking and freeing the cams with movement of the arm.

3. A shedding mechanism for looms comprising in combination with levers, actuating cams, a balance arm receiving an up and down movement from the loom, a double pawl carried by the arm and adapted to move therewith, a ratchet rigidly mounted with the cams and engaged by the pawls for 40 rotating said cams, a star wheel operatively connected to said cams and a segment mounted to move in unison with the balance arm, and adapted to engage said wheel with the down movement of said arm whereby to 45 lock the cams against rotation.

4. A shedding mechanism comprising in combination with levers, rotatable cams actuating said levers, a movable arm operatively connected to said cams to rotate the same, and means associated with said arm and cams for locking and freeing the latter with movement of the arm. 50

5. A shedding mechanism comprising a frame, a plurality of levers carried by the frame, a cam shaft for actuating said levers, a movable arm operatively connected with said cam shaft to rotate the same, a brake member mounted on a cam shaft and means associated with said arms and cam shaft for 55 locking and freeing the latter with movement of the arm.

In testimony whereof I have signed my name to this specification.

ANTONIO CALVET RIFÉ.
